UNITED STATES PATENT OFFICE.

CHARLES BYRON BRITTON, OF BROWNING, MISSOURI.

INTERNAL-COMBUSTION ENGINE.

Application filed March 28, 1924. Serial No. 702,676.

This invention relates to internal combustion engines, and more particularly to rotary engines.

An object of the invention is the provision of an engine having a piston carried by a rotating member secured to the main shaft and a casing in which the piston is adapted to rotate, together with means for closing a portion of the casing to form an explosion chamber, said means being automatically moved by suitable control mechanism upon each revolution of the piston to permit passage of the piston.

A further object of the invention is to provide a rotary engine in which the number of parts are reduced to a minimum.

A further object of the invention is to provide improved means for feeding the charge to the cylinders.

In the accompanying drawings, I have shown one embodiment of the invention.

In this showing:

Figure 1 is a central longitudinal sectional view,

Figure 2 is a horizontal sectional view on line 2-2 of Figure 1,

Figure 3 is a similar view on line 3-3 of Figure 1,

Figure 4 is a perspective view of one of the abutments by means of which portions of the casing are closed to form an explosion chamber,

Figure 5 is a vertical sectional view of the valve,

Figure 6 is a vertical sectional view of a portion of the casing and associated parts in the same plane as Figure 1 on an enlarged scale,

Figure 7 is a horizontal sectional view on line 7-7 of Figure 1, and,

Figure 8 is a detail view of a portion of the oiling mechanism.

Referring to the drawings, the reference numeral 1 designates a main shaft which is supported in suitable bearings and mounted in a lower frame 2. The frame is substantially cylindrical and may be provided with a plurality of braces 3 adapted to support the shaft. As shown, suitable roller bearings 4 are arranged between the braces and collars 5 carried by the shaft. The top of the frame is shaped to form a motor casing 6 which extends through an entire circle and which is preferably circular in vertical cross section. A carrier 7 is mounted on suitable arms or spokes 8 secured to the shaft

by means of a key 9 and this carrier extends through a chamber 10 into the motor casing. The inner face 11 of the carrier is curved to conform to the wall of the casing. Suitable roller bearings 12 are arranged in the chamber 10 above and below the arms 8 and the carrier is provided with suitable rings 13 to prevent leakage. As shown (see Figure 2), pistons 14 are supported by the carrier. Any number of these pistons may be employed but in this illustration, I have shown two pistons arranged diametrically opposite each other. An abutment 15 is adapted to close off portions of the casing to form an explosion chamber. This abutment consists of a substantially rectangular member adapted to slide in a valve casing 16 and provided with a semi-circular face 17 adapted to conform to the walls of the motor casing. As shown, the valve casing 16 is connected to the motor casing through a passage 18. A ring or packing member 19 is arranged on the surface of the abutment and this ring is retained in operative position by means of springs 20, secured to the rear of the abutment. The sides of the abutment are provided with grooves 20' adapted to receive rods 21 formed on the walls of the chamber 16 to guide the abutment. The abutment is controlled by means of a pivoted lever 22 having a forked upper end providing a pair of arms 23. A pin 24 extends through slots 23' in these arms and through the abutment. The lever 22 is pivotally mounted on a bracket 24' and is provided with a slot 25 in its lower end adapted to receive an operating member 26. The other end of the operating member is provided with a finger 27 adapted to engage cams 28 carried by a plate 29 secured to the main shaft. Springs 30 are arranged on the operating members 26 and are adapted to normally retain the abutments in closed position.

A pump 31 is arranged adjacent the engine and is connected to the main shaft by means of a belt 32. This pump is adapted to deliver air to a compressed air tank 33. The tank may be provided with a suitable safety valve 34. A pipe 35 extends from the air tank to a mixing chamber 36. This chamber is provided with a valve 37 normally retained in closed position by means of a spring 38 which surrounds the valve stem 39. The end of the valve stem is adapted to engage the periphery of the plate 29 to

operate the valve, and permit a charge of compressed air to be delivered to the mixing chamber. A fuel pipe 40 extends into the mixing chamber and is provided with a nozzle 41 on its end. The motor casing communicates with the mixing chamber through an inlet passage 42, normally closed by means of a valve 43. This valve is retained in closed position by a spring 44 and is adapted to be opened by suction. Suitable exhaust valves 45 are arranged in the casing, these valves being normally closed by springs 46. The valve stems are connected to fingers 47, pivotally mounted in brackets 48 and the ends of the fingers are adapted to be received in grooves 49 formed on plates 50. These plates are carried by the arms 8 of the carrier and revolve therewith. Adjacent each of the abutments, there is provided a spark plug 51 which is adapted to ignite the charge in the usual manner.

Suitable means are provided for oiling the parts of the engine. A quantity of lubricating oil is adapted to be placed in the bottom of the main casing 2 and a feed pipe 52 extends upwardly therefrom. This feed pipe is provided with a check valve 52' adjacent its upper end and communicates with a pipe 53 which serves as a pump cylinder. A piston 54 is arranged in the cylinder and a spring 55 surrounds the piston rod. The outer end of the piston rod is provided with an enlargement 56 adapted to be engaged by a lug 57 carried by the rod 26. The pipe or cylinder 53 communicates with a pipe 58, the other end of which is arranged above the motor casing and is adapted to return excess oil to the bottom of the main casing. The pipe 58 communicates with an oiling device 59 having a reduced passage 60 and having a ball valve 61 arranged beneath the reduced passage. An oscillating valve 62 is arranged above the reduced passage 60 and is provided with an opening 63 adapted to be periodically brought into alignment with the passage. The valve is normally retained in closed position by means of a spring 64 surrounding the valve stem 65. The upper end of the valve stem is provided with a lateral extension 66 adapted to be engaged by an operating lever 67 which is slidably mounted in a bracket 68. A cam 69 carried by the main shaft is adapted to reciprocate the lever to oscillate the valve. The motor may be provided with a cover 70 retained in position by suitable fastening elements 71.

In operation, the abutments 15 are normally in the position shown in Figure 2 of the drawings, closing the casing 6 and dividing it into two sections. As the carrier and pistons rotate, the finger 27 rides over the cam surface 28 of the plate 29 pulling the operating lever 26 inwardly and thus

moving the abutment to the position shown in Figures 1 and 6 of the drawings, thus permitting the piston to pass. The spring 30 is then placed under tension and as soon as the finger rides off the cam 28, the abutment assumes the closed position. As the piston passes beyond the suction valve 43, the valve is opened, permitting a charge to enter the casing between the piston and the abutment in the rear of it, which has then assumed the closed position. The spark plug 51 then furnishes a spark at the proper time to ignite the charge and force the piston around in the cylinder. As the piston approaches the end of a stroke, the fingers 47 are swung on their pivots to open the exhaust valves and permit the burned gases to discharge.

The reciprocation of the oil pump piston 54 draws a charge of oil upwardly through the pipe 52 and due to the check valve in the pipe 52, the next stroke forces the oil upwardly through the pipe 58. The oil is fed to the motor casing drop by drop by means of the valve 63 which is oscillated by the cam lever 67 to dispose the valve opening 63 in alignment with the reduced passage 60.

It is to be understood that the form of my invention herewith shown and described is to be taken as a preferred example of the same, and that various changes in the shape, size, and arrangement of parts may be resorted to without departing from the spirit of the invention or the scope of the subjoined claims.

I claim:

1. In a device of the character described, a circumferential casing, said casing being provided with an opening on its inner side, a main shaft arranged concentrically of said casing, a carrier connected to said shaft and extending through said opening, said carrier being provided with a periphery shaped to conform to the interior wall of said casing, pistons arranged on said carrier, abutment chambers on the outer side of said casing, the outer wall of said casing being provided with slots communicating with said abutment chambers, abutments slidably mounted in said slots, a pivoted lever connected to each of said abutments, a radially disposed slidable rod connected to each of said levers, a substantially flat plate carried by said shaft, cams mounted on said plate, hooks formed on the ends of said radially disposed slidably mounted rods and adapted to engage said cams, normally closed exhaust valves arranged in said casing, and pivoted fingers connected to said valves, said carrier being provided with grooves adapted to receive the other ends of said fingers.

2. In a device of the character described, a circumferential casing, said casing being provided with an opening on its inner side, a

main shaft arranged concentrically of said casing, a carrier connected to said shaft and extending through said opening, said carrier being provided with a periphery shaped to conform to the interior wall of said casing, 5 pistons arranged on said carrier, abutment chambers on the outer side of said casing, the outer wall of said casing being provided with slots communicating with said abut- 10 ment chambers, abutments slidably mounted in said slots, a pivoted lever connected to

each of said abutments, a radially disposed slideable rod connected to each of said levers, a substantially flat plate carried by said shaft, cams mounted on said plate, hooks 15 formed on the ends of said radially disposed slideably mounted rods and adapted to engage said cams, and a lubricating pump operatively connected to one of said slideable rods to be actuated thereby. 20

In testimony whereof, I affix my signature.
C. BYRON BRITTON.
